(57) **CLAIM**

The ornamental design for a rechargeable candle light combination, as shown and described.

DESCRIPTION

FIG. 1 is a perspective view of a rechargeable candle light combination according to the present invention, in which four candle-shaped light sources are disposed within a base charging unit.

FIG. 2 is a left side elevational view of the rechargeable candle light combination, with the right side elevational view being substantially identical to the left side elevational view, the only difference being the configuration of the top portion of the flame.

FIG. 3 is a top plan view of the rechargeable candle light combination, the bottom surface being unornamented.

FIG. 4 is a front elevational view of the rechargeable candle light combination, with the rear elevational view being a mirror image of the front elevational view; and,

FIG. 5 is a perspective view of the rechargeable candle light combination with one of the candle-shaped light sources removed from the base charging unit.
